DESIGN FOR A BOTTLE

Harry H. Wise, Chicago, Ill.

Application August 21, 1935, Serial No. 58,233

Term of patent 7 years

To all whom it may concern:

Be it known that I, Harry H. Wise, a citizen of the United States, residing at Chicago, in the county of Cook and State of Illinois, have invented a new, original, and ornamental Design for a Bottle, of which the following is a specification, reference being had to the accompanying drawing, in which Fig. 1 is an elevation and Fig. 2 a plan view of the article showing my new design.

I claim:—

The ornamental design for a bottle, as shown. In testimony whereof I affix my signature.

HARRY H. WISE.
